UNITED STATES PATENT OFFICE

2,291,075

CARTON OPENER

Harry Hanson, Menomonie, Wis.

Application April 23, 1942, Serial No. 440,243

3 Claims. (Cl. 30—2)

This invention relates to carton openers, of a generally similar type to that constituting the subject matter of my United States Patent No. 2,272,116, issued on February 3, 1942, on which the present device constitutes an improvement.

An important object of the invention is to provide, in a manner as hereinafter set forth, a carton opener of the aforementioned character comprising a guide embodying a novel construction and arrangement whereby said guide may be expeditiously swung to an out-of-the-way position when desired, thus permitting the device to be conveniently used adjacent the corners of the carton or on the face of any of the walls or the top thereof.

Another very important object of the invention is to provide a carton opener of the character described comprising unique means for adjustably securing a conventional safety razor blade in position to be used as the cutting element.

Other objects of the invention are to provide a carton opener of the character set forth which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a top plan view of a carton opener constructed in accordance with the present invention, showing the device in use on a corner portion of a carton.

Figure 2 is a bottom plan view of the device.

Figure 3 is a top plan view of the device with the guide in inoperative position.

Figure 4 is a cross-sectional view, taken substantially on the line 4—4 of Figure 2.

Figure 5 is a detail view in plan of the guide.

Figure 6 is a detail view in end elevation of the guide.

Figure 7 is a detail view in plan of the gauge.

Figure 8 is a view in side elevation of the gauge.

Figure 9 is a fragmentary view in section, taken substantially on the line 9—9 of Figure 2.

Referring now to the drawings in detail, it will be seen that the embodiment of the invention which has been illustrated comprises a substantially angular handle 1 of tubular form, said handle being of any suitable material. Formed

integrally with one side portion of the handle 1 is a plate 2.

Adjustably mounted on the plate 2 is a gauge 3. The gauge 3 includes a shoe 4 which projects forwardly past the angularly extending end portion 5 of the handle 1 and terminates in a curved lip or the like 6 whereby said shoe will ride easily over obstructions. The gauge 3 further includes a substantially segmental flange 7 which extends at right angles and rearwardly from the shoe 4 and which is adapted for side abutting engagement with the plate 2. The flange 7 has formed therein a pair of inclined slots 8 and 9. These slots 8 and 9 accommodate bolts 10 and 11 which are mounted in the plate 2.

Also mounted on the bolts 10 and 11 is a safety razor blade 12. The bolts 10 and 11 are so arranged that, as illustrated to advantage in Figure 3 of the drawings, the blade 12 is mounted 20 diagonally with respect to the plate 2, a corner portion of said blade extending past the rear end of the shoe 4 for engagement with a carton to be opened, as at 13.

The bolts 10 and 11 also have mounted thereon 25 a guide 14. The guide 14 comprises an offset flange 15 having formed transversely therein, at an intermediate point, a closed slot 16. The flange 15 is further provided, in its end portions, with arcuate, open slots 17 and 18. The slot 16 30 is for the reception of the bolt 10. The slot 17 accommodates the bolt 11 when the guide 14 is in operative position and the slot 18 accommodates said bolt when said guide is in inoperative position. At its forward end, the guide 14, which is 35 of substantially segmental form, is provided with an outwardly curved lip 19 to facilitate riding over obstructions.

It is thought that the manner of using the device will be readily apparent from a consideration of the foregoing. Briefly, when the opener is to be used for removing the top of a carton, as seen in Figure 1 of the drawings, the shoe 4 is moved along the side walls of said carton with the guide 14 riding on the top thereof. Of course, the protruding portion of the blade 12 penetrates and cuts the carton at a point closely adjacent the top thereof. The shoe 4 of the gauge 3 positively limits the depth to which the blade 12 may cut. In this manner damaging of 45 the contents of the carton is prevented. By loosening the nuts 20 and 21 on the bolts 10 and 11, the guide 3 may be conveniently and accurately adjusted as desired on the plate 2. When the device is to be used at a point remote from the corners of the carton, the nuts 20 and 21 are 50 55

loosened and the guide 14 is swung around on the bolt 10 into the tubular handle 1. When this is done, the slot 16 permits the reversed guide 14 to be pushed into the handle 1, the arcuate open slot 18 receiving the bolt 11. The nuts 20 and 21 are then tightened and the device is again ready for use.

It is believed that the many advantages of a carton opener constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

1. A carton opener of the character described comprising a substantially tubular handle having an opening therein, a plate on said handle, 20

a cutting blade mounted on said plate, and a guide rotatably mounted on the plate and engageable in the handle when not in use.

2. A carton opener of the character described comprising a substantially tubular, angular handle having an opening therein, a plate integral with said handle, a blade mounted on said plate, a gauge mounted on the plate, and a guide rotatably and slidably mounted on the plate and engageable in the handle when not in use.

3. A carton opener comprising a substantially tubular handle having an opening therein, a plate on said handle, a blade adjustably mounted on the plate, a gauge for said blade adjustably mounted on the plate, a guide rotatably mounted on the plate and engageable in the handle when not in use, and common means for securing the blade, the gauge and the guide in position on the plate.

HARRY HANSON.
